ATTORNEY

UNITED STATES PATENT OFFICE.

SAMUEL S. SADTLER, OF SPRINGFIELD TOWNSHIP, MONTGOMERY COUNTY, PENNSYLVANIA, ASSIGNOR TO AMIESITE FOUNDATION COMPANY, A CORPORATION OF DELAWARE.

CONSTRUCTION OF ROADS.

Application filed August 28, 1928. Serial No. 132,135.

In the ordinary manner of making black surfaced roads, the roadbed is prepared by excavating the soil to the proper depth and grade to receive a foundation course or 5 layer of broken stone, cement or other foundation material; by then placing on the roadbed thus prepared, the said foundation material and on that the top or surface course. But I have found that when a road 10 is to be built in and through certain sand-clay or clayey soils, the earth which is removed for the reception of the foundation course may be readily treated and then utilized as the main or principal ingredient or 15 constituent of the foundation course.

It is the object, therefore of my invention to utilize and to incorporate into the material of the road foundation much of the soil excavated in preparing the roadbed 20 and to so work or treat such soil or earth as to produce therefrom a highly satisfactory permanent, somewhat yielding or resili- 75

A further object of my invention is to 25 lessen the cost of road construction through certain soils by making it unnecessary to prepare and transport to the road-making operation, broken rock or other materials commonly used as the main constituent of a 30 foundation course and to utilize and substitute therefor the clayey soil which was removed in making the roadbed.

A further object of my invention is to 35 provide a road foundation which is resili- 80 ent or slightly yielding and in which is incorporated means to distribute the load of the traffic on the surface course over a relatively large area of the foundation course.

A further object of my invention is to pro- 40 vide a road construction with one or more intermediate courses or layers of fabricated material operative to distribute the load of traffic on the surface course over a relatively large area of the foundation course.

A further object of my invention is to pro- 45 vide a roadway, the chief ingredient of which is clayey or sand clay soil; to protect said course when laid from the action of any water which may pass through the upper 50 course or courses of the road; and to interpose between the foundation course and yielding top course, a layer or course of fabricated metal operative to spread the

weight of traffic on the upper course over a relatively large area of the foundation course. 55

Other objects of my invention will appear in the specification and claims below.

In the drawing forming a part of this specification and in which the same reference characters are employed throughout the 60 various views:

Fig. 1 is a diagrammatic view in transverse cross-section showing the curbing and the foundation course in place and then in spaced relationship thereover, the various 65 courses or layers employed in constructing the road embodying the invention of this application.

Fig. 2 is a similar cross-sectional view of the road after the courses have been placed 70 in order upon the foundation.

The above drawings are not strictly to scale. The thickness of the weight distributing courses and size of the mesh of the fabricated metal course are greatly exag- 75

gerated for the sake of making clear the construction.

It is desirable that there be on both sides of the road a retaining wall, curb or cement gutter to prevent any lateral movement of 80 the foundation due to traffic thereover or the action of the elements. In preparing the road, therefore, I excavate in the soil 1, a trench or channel the width of which is the full width of the roadbed including the 85

width of the curbing, and the bottom 2 of the trench (or top 2 of the roadbed) is brought to the proper grade and crown. I then preferably place the curbing 3 along both sides of the roadbed 2. This curbing 90 3 may be of any approved type and may be and preferably is of concrete cast in the usual wooden molds or against mold boards spaced from the outer sides of the excavation and serving to retain the moist or wet 95 concrete in position until the cement or concrete sets, after which the mold or molding boards may be removed, leaving the concrete curbing 3 in place where it was cast. Where the roadbed is normally wet or drain- 100

ing is required, I may provide French drains 4 in the top surface of the roadbed 2 to be filled with any suitable material 5, such as cinders, broken stone or even my foundation material referred to below, or 105 any other material which will permit of the

slow flow of water therethrough to keep the foundation dry.

I may then preferably drive into the roadbed suitable stakes 6 preferably creosoted 5 and preferably bringing the tops of the stakes to substantially the plane to which the roadbed is to be filled with foundation material. These stakes 6 may be suitably spaced and positioned, for use in making 10 the foundation course of the proper thickness, but I prefer to have one series or row of stakes 6 rather near the curbing 3 for purposes to be referred to again below.

After the roadbed 2 has thus been formed, 15 the curbing set and the roadbed staked, I may prepare my foundation material by mixing the soil, which was removed in excavating for the roadbed, with cement and hydrated lime thoroughly mixing these 20 three constituents together in any suitable manner, as in a pug mill, or other mixing apparatus, in the presence of water. The action of the lime is to render any clay in the soil non-plastic and to act as a binder 25 and filler with the cement used. In making this foundation, I prefer to mix substantially five to ten parts by volume each of cement and hydrated lime with substantially one hundred parts by volume of the soil in the 30 pug mill or other mixer in the presence of water. Caustic lime may be used, but it must be hydrated just before or during the mixing. A sufficient amount of soil is put into the mixer, the mixer is started, and the 35 lime and cement are added and then the water. The amount of water to be added should be sufficient to enable the mixer to be dumped and the contents spread with little effort to the proper level. The amount of 40 water, therefore, will depend upon the character of the soil, and somewhat upon the wetness of the soil itself. Clayey soil requires more water than sandy.

After a thorough mixing of these materials has been accomplished, the contents 45 of the mixer are dumped upon the top of the roadbed 2 and spread to the proper grade and level, as may be indicated by the tops of the stakes 6. Since there will be a slight 50 shrinking of the wet mix in drying, especially with clayey soil, the foundation course 7, so formed and placed, should cover the tops of the stakes 6 by probably half an inch.

It is desirable to have an excess of lime so 55 that it will react with carbon dioxide of the air and allow calcium carbonate to be formed to densify the mass.

After the mix thus prepared has been 60 placed in the roadbed to form the foundation course 7, it should be allowed to partially dry. When it is hardened sufficiently to be firm, it is rolled with a heavy roller to compact it, and then allowed to dry and 65 set more fully.

In preparing the foundation mix I may add to it the soluble salts of the iron and aluminum groups, such, for instance, as ferrous sulphate or aluminum sulphate. These chemicals react with the lime, to release the ferric hydroxid and aluminum hydroxid. Their action is to shorten the time required for the mix to set. These soluble salts may be mixed with the water which is added in the making of the foundation material or they may be mixed with the lime and added to the soil with the lime. I generally use about 10 pounds more or less of either of these salts per cubic yard of the mix.

After the foundation 7 has thus been placed and compressed by a roller as above described, it may be and preferably is covered with a layer or course 8 of tarred roofing paper. The strips 8" of paper are so placed on the foundation that their adjacent edges overlap in a manner to shed water.

Over this tarred paper course 8, is laid a metallic open mesh fabric 9 which may be regular galvanized chicken wire of preferably about one inch mesh and the edges of adjacent strips are wired or bound together. This wire fabric course 9 extends over the full width of the roadbed and preferably laps up against the curbing 3. After having been placed I prefer to secure this fabric and the tarred paper beneath it to the tops of the stakes 6 by fastening means such as nails, staples or the like, to hold the wire fabric 9 from lateral or transverse movement. The chicken wire 9 is preferably galvanized and in six foot widths. The edges should be joined together with a galvanized wire lacing and the strips should be stretched when fastening them to the stakes 6. The edges of the wires should be securely fixed to the posts next adjacent to the concrete curbing 6. It is desirable to secure this wire mesh fabric to stakes at or near the sides of the road and this is the reason why I have above stated that one row of stakes 6 are preferably adjacent the curbing. It is, of course, understood that these stakes or posts 6 may be driven in the roadbed for the mere purpose of securing the wire mesh fabric thereto but when stakes or posts are used to indicate the level to which the foundation is to be brought they may be utilized to also form suitable anchorages for the wire mesh fabric, particularly along the sides of the road near the curbing.

Before or after the wire mesh fabric 9 has been placed a thin layer or course 11 of liquid asphaltic material may be spread or painted over the tarred paper 8. The purpose of this asphaltic material is to provide a layer or course of waterproofing material for the foundation course 7 and to thoroughly coat the strands of the wire fabric with asphalt to protect them from corrosion.

By spreading the layer 11 of asphalt over the chicken wire course 9 after the latter has been placed and secured to the stakes 6, the wire strands of the wire fabric are perhaps better coated with the asphalt than when the asphaltic layer 11 is spread on the foundation on tarred paper course 8 prior to fastening the wire mesh fabric in place.

The top or surface course 12 is then placed 10 on the course of reticular metal fabric 9. This surface or top course 12 may be of any suitable surfacing material but it is preferably a black surfacing material, such as Amiesite, and composed of a lower layer 15 12' of broken stone coated with asphalt and of a size that would not pass through a 1 1/2" screen and be retained on one of 3/8" (both with circular openings), and an upper or surface course or layer 12" consisting of 20 smaller pieces of broken stone similarly coated or covered with asphalt composition. This surface course 12 so placed is rolled and compressed by a suitable roller and I preferably sprinkle over the surface after 25 rolling a thin layer 13 of sand or dust to more perfectly seal the surface. In some cases, only a single course such as 12' is used, instead of two courses as above referred to.

In some localities or under some circumstances, it may be possible and desirable to omit the retaining walls or curbing 3 in which event the foundation material is 30 preferably made in two batches, one the regular or standard mix, such as has been above described, and the other a like mix to which has been added rather more cement, say two or three times the amount. This cement-like mixture should be run or spread 35 on both sides of the roadway for about 9 to 18 inches in width. In other words, the foundation thus made would consist of two edges or strips along the side of the road, located about where the curbing 3, shown 40 in the drawing, is located and about 9 to 18 inches wide. Between these strips or bands of stronger mix the main body or mass of the foundation is composed of the regular mix above described. The two mixtures are 45 prepared and laid at the same time. The cement-like mixture at the sides of the road acts, as does the curbing, to prevent any lateral movement of the foundation.

Under some circumstances I may omit 50 from the road construction the course 8 of tarred paper and the mesh fabric 9 above described. The chief value of the wire mesh is to make the road more rigid while the foundation is becoming more and more firm 55 and compact.

The thickness of the tarred paper course 8 and the thickness of the wire fabric course 9 and the mesh of the wire fabric 9, as shown 60 in the drawings, are greatly exaggerated as to dimensions. The mesh of the wire fabric

9 is in practice less than the diameter of the stones forming the lower part 12' of the upper or surface course 12. The nails or tacks 10 and the posts 8 are also shown on an exaggerated and enlarged scale for the 70 sake of clearness. In Fig. 2 the roadway is illustrated as comprising a course of liquid asphalt 11 resting on the top surface of the wire mesh fabric. As a matter of fact, the asphalt or oil thus applied enters into the 75 interstices of the wire mesh, covers the wire thereof and lies on the top surface of the tarred paper course 8 after it has been applied, and the layer stones on the bottom part of the surface course 12 in practice, 80 rest of course, upon the wire mesh fabric 9 above described.

When the road is to be made in very sandy soil or in sand itself, before this foundation mixture is prepared and laid as a foundation course, I preferably wet the roadbed 2 with water so that the water contained in the mixture will not flow from the mixture into the roadbed before a chemical reaction 85 between the materials in the foundation has 90 been effected.

This mixture so formed is quite plastic, can be readily placed in and around the roadbed and brought to suitable crown and grade. With a foundation thus prepared, 95 the tarred paper course 8 might possibly be omitted but the course 9 composed of the wire mesh fabric coated with asphalt as above described, for distributing the load on the top course 12 over a considerable 100 area of the foundation course 7 is more vital to my invention.

After the wet foundation 7 has thus been placed on the roadbed 2, it should be allowed 105 to stand until it is capable of supporting a road roller.

The foundation 7 having thus been placed and compressed by rolling, the course 9 of wire mesh fabric is secured to the tops of the stakes 6, suitably placed therein, and a 110 coating or course 11 of liquid asphalt is applied to the chicken wire fabric and to top surface of the foundation course 7. Any suitable surfacing material, such as Amiesite, may be laid down as a top or 115 surface course 12 and rolled, in the manner above indicated.

The French drains 4 are placed wherever found desirable to have them and may be filled with any suitable material 5 such as 120 cinders or clayey earth that has been heated or baked to a temperature of about 250°, or with a mix of sandy soil and lime.

The surface course 12 which is preferably 125 Amiesite, comprises a broken graded stone, pieces or the particles of which are thoroughly coated with an asphaltic composition and when placed is rolled cold. It yields slightly under the load of traffic. It does not spread under such traffic or roll up 130

in advance of the wheels of a heavy vehicle. It is merely somewhat elastic or resilient due to the fact that the asphaltic material, by means of which the solid content of the 5 surface course is bound together, is not a rigid material. Therefore, when the load of traffic is applied to a narrow or small area of the surface course such as the relatively small area of contact between the 10 wheels of a vehicle and the roadway over which the vehicle is traveling, that pressure on that comparatively small area of the course 12 is imparted to the wire mesh fabric course 9 and by it is distributed over a 15 relatively large area of the foundation course 7. Such large area of my improved foundation material over which the load of traffic is thus distributed is amply sufficient to support the load of traffic without creeping or spreading and without being depressed or compressed, and without moving in any direction.

The rigid firm retaining walls or curbing 4 likewise hold the foundation 7 as well as 25 the top course 12 of the road from lateral or transverse movement. The road as a whole, is firmly retained between the curbing 3 on opposite sides of the road with the result that a foundation, composed and laid 30 as above described is a very permanent one, capable of withstanding without undue wear, heavy traffic thereon, and fully and completely protected from the action of water thereon. By lapping the edges of the open 35 mesh fabric up against the curbing 3 and then compressing it between the upper course 12 of the roadway and the curbing 3 the wire fabric 9 is firmly embedded in the bottom of the upper or surface course 12 40 and the ends of it are substantially clamped between the said upper course 12 and the immovable curbing 3.

Having thus described my invention, what I claim and desire to protect by Letters 45 Patent of the United States, is:

1. The method of constructing a roadway in a sand-clay soil, which consists in excavating and leveling the soil to the grade of the roadbed, mixing the excavated soil with 50 cement, calcium hydroxide and water, and stirring the same together until the mixture is uniform throughout and then placing a course of the mixture so made on the roadbed and compacting the same to form a foundation course, and allowing same to set and dry.

2. The method of constructing a roadway in a sand-clay soil, which consists in excavating and leveling the soil to the grade of 60 the roadbed, mixing the excavated soil with not more than 10% by volume each of cement and calcium hydroxide calculated to the soil or sand used, and stirring the same together in the presence of water until the 65 mixture is uniform throughout and then

placing a course of the mixture so made on the roadbed and compacting the same to form a foundation course, and allowing same to set and dry.

3. The method of constructing a roadway 70 in a sand-clay soil, which consists in excavating and leveling the soil to the grade of the roadbed, mixing the excavated soil with about 5% by volume of cement and about 10% by volume of calcium hydroxide, calculated to the soil or sand used, and stirring the same together in the presence of water until the mixture is uniform throughout and then placing a course of the mixture so made on the roadbed and compacting the same to 75 form a foundation course, and allowing same to set and dry.

4. The method of constructing in a clayey soil, a foundation for a roadway having a surface course which yields slightly under 80 the load of traffic, which consists in leveling the soil to the grade of the roadbed, placing rigid means on opposite sides of the roadway for preventing the lateral movement of the 85 foundation course, mixing the excavated soil with cement, hydrated lime and water, and stirring the same together until the mixture is uniform throughout, placing a course of the mixture so made on the roadbed allowing the placed material to harden sufficient- 90 ly to support a roller, and then compacting the same to form a foundation course, providing said foundation course with stakes, the top ends of which are flush with the top surface of said foundation course, placing 95 on the said foundation a course of fibrous material, placing on said fibrous material a course of open mesh metal fabric, stretching said metal fabric and securing it fixedly to the tops of said stakes, and applying a liquid 100 asphaltic material to said metal fabric and to the upper surface of said fibrous material 105 to coat said fibrous course and said metallic fabric.

5. The method of constructing in a clayey 110 soil, a foundation for a roadway having a surface course which yields slightly under the load of traffic, which consists in excavating and leveling the soil to the grade and crown of the roadbed, mixing the excavated soil with cement, hydrated lime and 115 water and thoroughly stirring said materials together to produce a mixture uniform throughout the mass thereof, placing a course of the mixture so made on the roadbed and allowing the placed material to 120 partially dry and then compacting the same to form a foundation course, placing on said foundation a course of fibrous material, comprising sheets of tarred paper with the 125 edges thereof overlapped to shed water, placing on said paper, strips of open mesh metal fabric with their adjacent edges bound together, fixedly fastening said metal fabric to said foundation course, and apply- 130

ing a liquid asphaltic material to said metal fabric and to the upper surface of said paper to protect the metal fabric from corrosion and to render said paper impervious to water.

6. The method of constructing in a clayey soil, a foundation for a roadway having a surface course which yields slightly under the load of traffic, which consists in excavating and leveling the soil to the grade of the roadbed, mixing the excavated soil with cement, hydrated lime and water in substantially the proportions by weight as follows: 100 parts by volume of said soil, 5 to 10 parts of cement, and 5 to 10 parts of said lime and sufficient water, and thoroughly stirring said materials together to produce a uniform distribution of said materials throughout the mixture, placing the mixture so made on the roadbed and compacting the same when sufficiently dry to form a foundation course, placing on said foundation a course comprising sheets of tarred paper having adjacent edges overlapped to shed water, placing on said paper course strips of open mesh metal fabric and rigidly securing the same and said sheets of paper to said foundation course and applying a liquid asphaltic material to said metal fabric and to the upper surface of said sheets of paper.

7. The method of constructing in a clayey soil, a foundation for a roadway having a surface course which yields slightly under the load of traffic, which consists in excavating and leveling the soil to the grade of the roadbed, mixing the excavated soil with cement, hydrated lime, soluble salts of the iron or aluminum groups and water, and thoroughly stirring said materials together to produce a uniform mixture throughout, placing a course of the mixture so made on the roadbed and allowing it to partially harden and then compacting the same to form a foundation, placing on said foundation a course of tarred paper and on that a course of open mesh metal fabric, and applying a liquid asphaltic material to said metal fabric and to the upper surface of said tarred paper.

8. The method of constructing in a clayey soil, a foundation for a roadway having a surface course which yields slightly under the load of traffic, which consists in excavating and leveling the soil to the grade and crown of the roadbed, laying a foundation course thereon consisting of the ex-

cavated clayey soil intimately mixed with substantially 5 to 10 parts of the weight of the soil of cement and 5 to 10 parts of hydrated lime, in the presence of water, laying on the foundation course, sheets of fibrous material having their adjacent edges overlapped to shed water, placing on said sheets strips of reticular metal fabric with their adjacent edges bound together, stretching said strips of metal fabric and fixedly securing the same to said foundation course, and coating said metal fabric and the upper surface of said sheets with a liquid asphaltic material.

9. The method of construction, in a clayey soil, a foundation for a roadway having a surface course which yields slightly under the load of traffic, which consists in excavating and leveling the soil to the grade of the roadbed, mixing the excavated soil with lime and water and stirring said ingredients together until the mixture is uniform throughout and of the consistency of freshly made cement, placing a course of the mixture so made on the roadway and compacting the same, allowing the said material to set and dry, placing on said cement-like course a sheet of reticulated metal fabric covered with a liquid asphalt composition and securing said sheet to said cement-like course, whereby when said surface course of slightly yielding material is laid on said metal fabric course, the load of traffic imposed upon a relatively small area of said yielding surface is distributed by said metal course over a relatively large area of said cement-like course.

10. In a roadway having a surface course which yields slightly under the load of traffic, a foundation course composed of clayey soil intimately mixed with hydrated lime and water to form a compact cement-like composition, a sheet of fibrous material upon the surface of said cement-like course and a sheet of reticulated metal upon said fibrous fabric sheet, said sheets of fibrous fabric and metal being covered with a liquid asphaltic composition and lying between said foundation course and said surface course, whereby the load of traffic imposed upon a relatively small area of said surface course is distributed by said metal course over a relatively large area of said foundation course.

In witness whereof, I have hereunto set my hand this 27th day of August, 1926.

SAMUEL S. SADTLER.
